G. A. AMSDEN.
CASH CARRIER.
APPLICATION FILED JULY 22, 1914.

1,303,811.

Patented May 13, 1919.

UNITED STATES PATENT OFFICE.

GEORGE A. AMSDEN, OF LITTLETON, MASSACHUSETTS, ASSIGNOR TO THE LAMSON COMPANY, OF BOSTON, MASSACHUSETTS, A CORPORATION OF MASSACHUSETTS.

CASH-CARRIER.

1,303,811.

Specification of Letters Patent. Patented May 13, 1919.

Application filed July 22, 1914. Serial No. 852,466.

To all whom it may concern:

Be it known that I, GEORGE A. AMSDEN, a citizen of the United States, residing at Littleton, in the county of Middlesex and 5 State of Massachusetts, have invented certain new and useful Improvements in Cash-Carriers, of which the following is a specification.

This invention relates to carriers for cash 10 and other small articles, such as are used in cable carrier systems, and has for one of its objects the provision of an improved locking device for such carriers.

Another object has been to secure a maximum 15 amount of protection for the cover of the carrier while at the same time affording the greatest amount of space within the receptacle, for a given size of the same.

These and other objects of my invention 20 will be hereinafter referred to and the novel elements and combinations of means whereby said objects may be attained will be more particularly pointed out in the claims appended hereto.

25 In the accompanying drawing which forms a part hereof and in which like reference characters designate like parts through the several views, I have exemplified a preferred construction; but as I am 30 aware of various changes and modifications which may be made herein without departing from the spirit of my invention I desire to be limited only by the scope of said claims.

35 In the drawing:

Figure 1 is a plan view of my improved carrier; a small portion of the cover being broken away to show the latch in its locking position.

40 Fig. 2 is a side elevation of said carrier; a portion of the side of the receptacle being broken away.

Fig. 3 is a bottom view of the carrier.

Fig. 4 is an end view of the same; and

45 Fig. 5 is a perspective view of a carrier in the hand of an operator, the lid or cover being in its partially open position with the latch in its closed or locking position; the view being designed to illustrate the advantage of the novel latch which is moved to its unlatching position by the thumb of the operator as the cover is being closed.

50 The carrier comprises the usual receptacle 1 with its cover 2, the latter preferably being hinged upon a pin 3; and a coiled spring

4 upon this pin, disposed between the hinged portions of the cover, normally tending to move the cover to its open position.

Secured to the bottom of the receptacle 60 is a fiber plate 5 below which is a second fiber plate 6 of somewhat narrower width; and a metallic base plate 7 is provided with guide lugs 7' which co-act with the corresponding edge portions of the plates 5 and 6 to retain the carrier in position upon its 65 rails when in transit in a known manner. The plates 6 and 7 may be recessed or slotted for the reception of the usual pivoted jaw 8 of the gripping device with which carriers of this description are usually provided; the 70 relatively fixed jaw 9 of the grip being secured to the bottom plate 7.

The details of the gripping device need not herein be further considered since these 75 parts *per se* form no part of the present invention.

Pivoted at 10 to the cover is a preferably 80 unitary or single piece sheet metal latch 11, which, as indicated in Figs. 1 and 2, is bent or offset, so that while the body 11' of the latch lies flat and in contact with the under surface of the preferably sheet metal cover, the actual latching end of the latch is spaced downwardly from said cover so as to permit of its passage under a projection 12, 85 preferably formed by slitting and driving in somewhat more than a sixteenth-inch thickness of the edge of the receptacle. The cover has the outer edge thereof nicked or recessed as at 13 to permit of its being closed, and when so disposed its upper surface is substantially flush with the upper edge of the receptacle 1, as indicated in Fig. 2.

90 This disposition of the cover is a particularly advantageous one, since while the cover must be protected against the possibility of edgewise blows which it might receive while in transit, I have found that it is by no means necessary that the cover be set well down into the receptacle in the manner which it has been customary heretofore to do in devices of this description.

95 By thus mounting the cover so that when closed its upper surface is flush with the 100 edge of the receptacle, I obtain ample protection for the cover while at the same time a maximum amount of space within the receptacle is obtained, the article holding space being substantially equal to the full 110

depth of the recess in said receptacle minus merely the thickness of the sheet metal cover.

The part or body 11' of the sheet metal latch which lies upon the inner side of the cover preferably has upon the outer end of such part a stud or handle 14 the shank of which is preferably reduced as at 14' to ride in a narrow arcuate slot 15' in the cover. If this form of handle is used, then the inner head 14" of the stud is preferably caused to bear against an upwardly arched spring member 15, the ends of which are upturned and bent over to form attaching ears, which latter may be riveted to the cover, as indicated in Figs. 1 and 2.

The member 15 extends obliquely with respect to the major axis of the carrier, so that it is directly beneath the slot 15' and thereby serves in part to close this slot, or at least prevent exposure of the contents of the receptacle or box therethrough; while further the inwardly arching spring fends the papers or the like which may be in the receptacle, away from a part of the latch.

The principal function, however, of the resilient member 15 is to hold the latch against inadvertent movement out of its locking position when so disposed, and conversely against movement toward its locking position when it should be in its unlatching position.

The reason for this is that when the carrier is in transit with the latch in its locking position to maintain the cover closed, the severe jolts and jars to which the carrier is subject during transit might cause the inadvertent release of the cover, the spring of which would thereupon move it to its open position and allow the contents of the carrier to drop out. On the other hand when the carrier has been purposely opened at a station and its contents removed, it is desirable that the latch remain in its unlocking position to facilitate re-closure of the cover.

It sometimes happens, however, that in spite of this provision of means for maintaining the latch in its open position when the box is empty, as the carrier is thrown around upon the desk of the cashier or at a clerk's station, the latch may be knocked into its locking position; and in such case the cover obviously cannot be altogether closed until the latch has been rotated counter-clockwise, as viewed in Fig. 5.

Here, the particular disposition of the latch handle, emphasized in said figure by the presence of the operator's thumb adjacent thereto, is of utility since, if the latch be disposed as shown in said Fig. 5, the very action of pressing the cover to its closed position by the thumb of the operator serves also, practically automatically, to swing the latch counter-clockwise; thus moving it to

its unlocking position to permit the continued pressure of the thumb to close the cover; whereupon a reverse movement of the stud 14 in its slot, by the thumb of the operator, locks the cover; the handle of the latch when the latter is in its fully opened position being most remote from the pivotal axis of the cover and being nearest to said axis when the latch is in its fully closed position; the entire travel of the handle when the latch is being closed being substantially directly back from its most remote position from said axis, toward the latter. This effects a slight saving in time for the operator under such conditions and in a busy store where many thousand carriers are being despatched each day such a saving of time may become very material. The inward movement of the cover may be limited in any suitable manner, but I prefer to again simply slit the wall of the receptacle at points spaced below the upper edge thereof about the thickness of the sheet metal cover, and to strike in, as at 16, the preferably sheet metal wall of the receptacle, immediately below these slits, so as to form small lips against which the cover may be seated.

Although the latch is upon the inside of the cover and is hence efficiently protected against injury while the carrier is in transit, despite the fact that the upper surface of the carrier is flush with the upper edge of the receptacle, the flat spring 15, covering as it does the outer end of the latch handle, prevents injury to the contents of the box as the latch is moved to its open or closed position; and the shape of the offset portion 11 is such that even though this part is spaced inwardly from the cover it does not tend to bite into papers or other articles in the receptacle, said portion 11 being given an inclination upwardly as its latching edge is approached, as indicated in Figs. 2 and 4; which results in the innermost portion 11' of the part 11 being spaced farthest from the cover and such innermost portion having but very slight movement owing to its nearness to the pivotal axis of the latch and tending to bear against any papers which may be in the receptacle and press them out of engagement with the latching edge, the movement of which into place beneath the lip or projection 12 might cause such papers to be mutilated. That this portion 11" will thus press down upon any papers in the receptacle and tend to hold them out of engagement with the free end of the latch 11 becomes evident upon an inspection of Fig. 4, since said portion 11" is the part of the latch which is nearest to the bottom of the receptacle when the cover is closed.

Further, this upwardly directing and camming of the under surface of the portion 11 favors the riding up upon said papers of the latching edge.

This feature may appear to be comparatively trivial, but in the exemplified construction it is largely by reason thereof that it becomes feasible to dispose the pivoted latch upon the underside of the cover rather than upon the outer side thereof; and, as above noted, this disposition of the latch permits the cover to be moved out flush with the edge of the receptacle to thereby increase 10 the capacity of the box.

I do not of course desire to be limited to the specific provisions shown for pressing papers or bills in the receptacle out of the way of possible mutilation by the locking 15 edge of the latch, but the construction shown has the merit of extreme simplicity.

I also particularly desire to call attention to the novel resilient member or spring 15, which has both of its ends firmly attached to 20 the cover, whereby to prevent possible injury to this member, such as might occur were one end to be free; the spring also being materially strengthened or stiffened by thus having both of its ends rigidly held.

25 Having thus described my invention what I claim is:—

1. A carrier for despatch apparatus comprising a receptacle having a cover hinged thereto, a bent sheet metal latch mounted 30 upon the inner side of said cover and having a body portion disposed substantially flatwise against said inner side of said cover, and a cover locking part offset from said body portion and out of parallelism with 35 the latter to constitute means to press papers or bills in said receptacle, which might otherwise be mutilated by movements of the latch, away from the portion of said cover locking part which has the greatest movement and which would thereby most tend to 40 mutilate said papers.

2. A carrier for despatch apparatus comprising a receptacle having a cover hinged

thereto and a bent sheet metal latch mounted upon the inner side of said cover and having 45 an integral portion, adjacent a locking edge thereof, adapted to press papers or bills in said receptacle which might otherwise be mutilated by said locking edge, away therefrom, said paper pressing portion being 50 removable with respect to said cover in correspondence with the movements of said locking edge.

3. A carrier for despatch apparatus comprising a receptacle having an apertured 55 cover hinged thereto, a latch mounted upon the inner side of said cover having a handle extending out through the aperture in said cover, and a resilient member adapted to hold said latch both in its locked and unlocked positions, said member having both ends thereof attached to said cover whereby to prevent possible injury to said member and strengthen the same.

4. A carrier for despatch apparatus comprising a receptacle having a cover hinged thereto, a coiled spring tending to open said cover, a latch pivoted upon said cover and adapted, when operatively disposed, to resist the action of said spring, and means to hold 65 said latch against inadvertent displacement when in its cover locking position, said means comprising an arched flat spring, both ends of which are attached to said cover, said spring arching downwardly into the receptacle when the cover is closed and fending 70 papers or the like which may be disposed in said receptacle, away from a part of said latch.

In testimony whereof I have affixed my 80 signature, in the presence of two witnesses.

GEORGE A. AMSDEN.
